UNITED STATES PATENT OFFICE.

WILLIAM N. MOTTER AND FREDERIC S. KOCHENDORFER, OF CHICAGO, ILLINOIS,
ASSIGNORS, BY MESNE ASSIGNMENTS, TO GENERAL ELECTRIC COMPANY, A
CORPORATION OF NEW YORK.

OSCILLATING-FAN MOTOR.

1,073,617.

Specification of Letters Patent. Patented Sept. 23, 1913.

Application filed May 7, 1909. Serial No. 494,574.

To all whom it may concern:

Be it known that we, WILLIAM N. MOTTER and FREDERIC S. KOCHENDORFER, citizens of the United States, residing at Chicago, in 5 the county of Cook and State of Illinois, have invented a certain new and useful Improvement in Oscillating-Fan Motors, of which the following is a full, clear, concise, and exact description.

10 Our invention relates to oscillating fans of the type in which a movable vane is adapted to be interposed automatically in the current of air set in motion by the fan for the purpose of unbalancing the pressure 15 of air on each side of the axis of the fan, and thereby causing said fan to oscillate from side to side on its standard.

The principal object of our invention is 20 to provide an oscillating fan motor in which the wind vane is placed in the position most effective in establishing an unbalanced condition in the pressure of the air set in motion by the fan, that is, in a position where the pressure of air is the greatest per square 25 inch, thereby making it possible to use a vane of minimum area for a given turning effort.

A further object is to convey the current 30 from the standard upon which the fan motor is pivoted to oscillate to the motor without the use of rubbing contacts, such as collector rings and brushes, thereby reducing to a minimum the friction incident to said rubbing contacts.

35 Our invention contemplates a vane adapted to revolve in the path of the current of air set in motion by the fan blades together with mechanism automatically operated during the oscillatory movement of the fan, 40 for stopping said vane on each side of the axis of the fan to maintain an unbalance in the air pressure on one or the other side long enough to cause said fan to oscillate on its standard, said mechanism being also 45 adapted to release said vane preferably near the end of each oscillation. In the preferred form of our invention the vane is carried at the ends of arms which are in turn carried by a hub frictionally mounted on the motor 50 shaft and driven thereby, said vane being

adapted to be revolved around the outer ends of the blades in a circle concentric to the axis of the fan.

Referring to the accompanying drawings, we will describe our invention in detail.

Figure 1 is a front elevation of an oscillating fan motor embodying our invention, the fan blades being partly broken away; Fig. 2 is a top view of said fan; Fig. 3 is a fragmentary view in front elevation showing the 60 stopping and releasing mechanism; Fig. 4 is a side elevation partly in section showing said mechanism in one of its engaging positions; Fig. 5 is a fragmentary view partly in section showing said mechanism in its 65 other engaging position and also showing the means for conveying the current from the standard to the motor; Fig. 6 is a sectional view in the direction of the arrows on line 6—6 of Fig. 5; Fig. 7 is a perspective 70 view of the vane and the hub in which it is carried; Fig. 8 is a view in elevation of the standard in which the motor is mounted to oscillate.

Similar reference characters are used to 75 designate like parts throughout the several views.

Our invention is particularly adapted to the usual desk type of fan motor such as we have shown in the drawings in which 1 indicates an electric motor adapted to drive a set of fan blades 2 carried on its shaft and 3 indicates the usual open-work guard surrounding the blades. Between the hub on which the fan blades 2 are mounted and the 80 bearing for the motor shaft 5, we provide a hub 4 on said motor shaft 5. This hub is preferably in frictional engagement with said shaft and is adapted to be frictionally driven in the same direction as the fan 90 blades and at a speed relatively slower than the speed of the fan blades. The hub 4 has projecting radially from it two arms 7—7 on the outer end of which is mounted a vane 6 bent to the curvature of the circle described by the outer ends of the fan blades and lying at right angles to the radii of said circle. The vane 6 is preferably adapted to be revolved in the space between the outer 95 ends of the blades 2 and the guard 3, and is 100

adapted to intercept a portion of the air set in motion by the fan, that is, in the preferred arrangement, it is adapted to move in the path of the air drawn into the fan, so to speak. The hub 4 is provided with a counterweight 4' to balance the weight of the vane 6.

In order that the vane 6 may maintain an unbalanced condition of the air pressure on one or the other side of the axis of the fan for a period long enough to cause said fan to acquire its proper oscillating movement, stopping and releasing mechanism is provided which is adapted, during the oscillatory movement of the fan, to automatically stop said vane on each side of the axis of the fan and to preferably release it when the fan has neared each end of its range of movement. This mechanism comprises a member 8 hinged at 9 to a plate 10 secured in any suitable manner to a downward extension 11 of the motor 1 and is adapted to oscillate with the motor and also to oscillate, that is to swing on its own hinge 9 through a limited range. The member 8 carries on its upper end the arms 12 and 13 which extend upwardly one on each side of the hub 4. The arm 12 is provided with a lateral projection 12' forming a hook, while the arm 13 is arranged with its end 13' cut off horizontally to form an abutment; the end 13' and the under edge of the hook 12' being arranged in a substantially horizontal line with the axis of the fan and are adapted when the member 8 is swung on its hinge to be interposed alternately in the path of a lug 4" carried on the hub 4. On the lower end of the member 8 is a rockshaft 14 adapted to rock in a suitable bearing in said member; this rockshaft being provided with an upwardly and downwardly extending crank-lever 15 and 16, respectively, on opposite ends thereof. The crank-lever 15 has secured to its upper end one end of a spiral spring 17, the other end of which is secured to the eyelet 18 on said member 8. The other crank-lever 16 is adapted to strike the stops 19 and 20 when the fan has neared each end of its range of movement. These stops determine the limits of the range of movement of the fan and may be placed in any of the holes 21 in the standard 22 to adjust said limits. The purpose of the rockshaft 14 and the spring 17 is to permit the crank-lever to yieldingly strike the stops 19 and 20 and to cause the fan to oscillate smoothly.

The downward extension 11 of the motor 1 is provided with a chamber 23 into which extends the upper end of the standard 22 upon which the motor is mounted to oscillate from side to side. The upper edge of the standard 22 and the bottom of the chamber 23 are preferably provided with corre-

sponding raceways 24 between which the 65 balls 25 are adapted to run to form a bearing for the motor to oscillate on, although any suitable form of bearing or pivot may be used. On the extension 11 near its lower edge is provided a screw 26 arranged to 70 project into a groove 27 around the standard to maintain the motor in its proper position on its bearing and at the same time, by the removal of said screw, to permit the motor to be easily disassembled from the standard. The standard 22 is provided at its upper end with a chamber 28 which contains at its bottom suitably insulated sockets 29 and 30 (Figs. 5 and 6) to which line wires 75 may be suitably connected to form terminals 80 therefor. Into these sockets are adapted to be removably inserted the plugs 31 and 32, respectively, carrying at their upper ends, and supporting in position, an insulating disk 33. On the upper and lower sides of 85 this disk are flat spiral conducting springs 34 and 35 oppositely wound and secured by their outer ends to the upper ends of the plugs 31 and 32, respectively. Extending downwardly from the motor casing and insulatedly supported thereby are two parallel conductors or rods 36 and 37 connected by their lower ends to the inner ends of the conducting springs 34 and 35, respectively. A hole 38 is provided in the insulating disk 95 33 to permit the conductor 37 to be connected to the inner end of spring 35, this hole being large enough to allow the conductor 37 to move freely therein when the motor is oscillated in its bearing. The conductors 100 36 and 37 form terminals for the leading in wires 39 and 40, respectively, of the motor. During the oscillatory movement of the motor on the standard the springs 34 and 35, being oppositely wound, neutralize each 105 other, hence, they offer no retarding force to the motor, and at the same time they form an unbroken connection between the motor and the standard and thus serve to properly conduct the current and to eliminate frictional losses and other objectionable features 110 incident to the use of moving contacts such as collector rings and brushes.

The operation of our invention as embodied in the structure shown in the drawings is as follows: When the fan is started in operation the vane 6 will be revolved on its hub 4 from any position in which it may previously have stopped, until it reaches one or the other of the positions shown in 120 dotted lines or full lines in Fig. 1, in which position the lug 4" will be engaged by either the hook 12' of the arm 12, or the abutting end 13' of arm 13, depending upon whichever side of the axis of the fan the 125 vane may have been revolved to. Assuming that the fan has been started and the vane revolved to the position shown in full lines

in Fig. 1 from some position intermediate of its positions shewn in said figure in which it may have previously stopped. The vane will be held in said position by the hook 12' 5 of arm 12 being in engagement with the lug 4'' on the hub 4. The vane will therefore unbalance the pressure of the air set in motion by the fan and cause said fan to oscillate in one direction in a manner well 10 understood in the art. The fan will continue to move in that direction until the crank-lever 16 strikes the stop 19 which swings the member to its opposite position, thereby removing the hook 12' from lug 4'' 15 to release the vane and interposing the end 13', of arm 13 in the path of the lug 4''. The vane will then be revolved to the position shown in dotted lines in Fig. 1, whence the end 13' of arm 13 will engage the lug 20 4'' and retain the vane in said position. The vane will again establish an unbalance 25 in the air pressure but on the opposite side of the axis of the fan, and the fan will move in the other direction until the crank-lever 16 strikes the other stop 20 and the vane 30 will again be released and the same cycle of operation will be again repeated.

In the preferred form of our invention the vane is driven frictionally by the motor 35 shaft, hence its movement is always positive and it will always be revolved to one or the other of its operative positions regardless of the position in which it may have previously stopped.

35 In the drawings we have shown the standard as being made up of two parts 41 and 42 clamped together in beveled relation by the bent bolt 43, the purpose of this arrangement being to permit the fan to be used 40 either as a wall type or a desk type. This construction, however, forms no part of our present invention, hence it is not particularly described.

We claim:

45 1. The combination with a motor and a fan driven thereby, of a vane frictionally driven by said motor bent to substantially the curvature of the circle described by the outer ends of the fan blades and lying at 50 right angles to the radii of the circle and adapted to revolve around the ends of the fan blades and to be stopped and released alternately on each side of the axis of the fan to cause said fan to oscillate from side 55 to side, and means operated in the oscillatory movement of the fan for alternately stopping and releasing said vane.

2. In an oscillating electric fan, the combination with a motor and a fan driven 60 thereby and a standard upon which said motor and fan are mounted to oscillate, of a vane frictionally driven by said motor bent to substantially the curvature of the circle described by the outer ends of the fan blades

and lying at right angles to the radii of the 65 circle mounted concentric to the axis of the fan and adapted to be revolved around the outer ends of the fan blades in the path of the air drawn into said fan, and means for automatically stopping and releasing said 70 vane to alternately unbalance the air pressure on each side of the fan to cause said fan to oscillate from side to side.

3. The combination with a standard, a motor and a fan driven thereby pivoted to 75 oscillate on said standard, a hub, and a vane carried thereby, frictionally mounted on the motor shaft and adapted to revolve concentrically with respect to the axis of the fan, a lug carried by said hub, a pivoted 80 bifurcated member arranged to oscillate with said motor and adapted during the oscillatory movement of said motor to interpose its arms alternately in the path of movement of said lug to alternately stop 85 and release said vane on either side of the axis of the fan.

4. The combination with a standard, a motor and a fan driven thereby, pivoted to oscillate 90 on said standard, of a hub and a vane carried thereby, frictionally mounted on said motor shaft and adapted to revolve in a circle concentric to the axis of the fan, a lug carried by said hub, a pivoted bifurcated member supported by said motor and 95 adapted to interpose its arms alternately in the path of said lug to stop and release said vane alternately on each side of the axis of the fan, stops on said standard at each end 100 of the range of movement of said fan and a yielding extension carried by said member adapted to strike said stops during the oscillatory movement of said fan to swing said member upon its pivot.

5. The combination with a fan and a 105 standard upon which said fan is mounted to oscillate from side to side, of a vane bent to substantially the curvature of the circle described by the outer ends of the fan blades and lying at right angles to the radii of the 110 circle and adapted to be revolved around the outer ends of the fan blades and to be arrested alternately on each side of the axis of the fan and held until said fan completes each oscillation, and means, automatically 115 actuated at the end of each oscillation, for releasing said vane and allowing it to be revolved to the other side of said fan and for simultaneously interposing a stop in the path of said vane to arrest said vane when 120 it reaches said other side.

6. The combination with a standard, of an electric fan-motor pivoted to oscillate upon 125 said standard, said standard having a chamber in its upper end terminal sockets in said chamber, an insulating disk and plugs carried thereby adapted to enter said sockets, parallel insulated conductors carried by the

motor and extending into said chamber, and flat opposed spiral springs, one on each side of said insulating disk, connected by one of their ends to said parallel conductors and by 5 the other of their ends to said plugs for conveying the current from the standard to the motor.

In witness whereof, we hereunto subscribe our names this 28th day of April A. D. 1909.
